Patented Sept. 30, 1919.

FIG. 2.

FIG. 10.

卷之二

四百四

Ellis H. Wallen, Jr.
By his Attorney
A. M. Conliffe.

UNITED STATES PATENT OFFICE.

ELLIS HUGO WALLANDER, OF MINNEAPOLIS, MINNESOTA.

CAR-STOPPING DEVICE.

1,817,239.

Specification of Letters Patent. Patented Sept. 30, 1919.

Application filed December 26, 1918. Serial No. 268,439.

To all whom it may concern:

Be it known that I, ELLIS HUGO WALLANDER, a subject of the King of Sweden, residing at Minneapolis, in the county of Hennepin and State of Minnesota, have invented a new and useful Car-Stopping Device, of which the following is a specification.

My invention relates to railway appliances, and the object is to provide an efficient device for stopping a railway car at any desired place on a track where it is intended to be stopped during switching operations without the expense of keeping a brakeman on each car for operating the brakes. The device is especially adapted for the so-called "fly-switching", in which one or more cars are given a push by an engine and then left to run by the momentum along upon some track and be there stopped by the brakes.

Instead of thus employing a brakeman on each car my device enables one man on the ground or car yard to stop any number of cars at predetermined places on the track.

In the accompanying drawing:

Figure 1 is an end elevation of a railway rail with my car stopping device and a car wheel placed upon it. Fig. 2 is a left hand side view of Fig. 1. Fig. 3 is a top view of Fig. 2. Fig. 4 is a section on the line 4—4 in Figs. 1 and 3 with the car wheel omitted.

Referring to the drawing, by reference numerals, 5 designates an ordinary rail of a railway track, upon which runs ordinary car wheels like 6, having a guiding flange 6* guiding against the inner side of the tread 7 of the rail.

The stopping device consists of an angle bar whose horizontal flange 8 is placed upon the tread of the rail and the vertical flange 9 is placed close against one side of the tread, preferably the inner side, so that the flange 6* of the wheel will prevent lateral displacement of the device the moment the wheel enters upon it.

The end of the bar directed toward the approaching wheel has both of its flanges beveled, as shown at 10, so as to make the wheel enter upon the bar without giving it a chance to push the device along the rail. The other end of the angle bar is formed

with a hollow head 11, having a segmental face 12 arranged to meet the face of the wheel 5.

In said face 12 is a large aperture 13, in which is loosely fitted a segmental-faced block 14, whose lower end is pivoted at 15, and the upper end is provided with an offset extension 16, which takes against the inner side of a flange or ledge 17 when the curved face of the block projects outward a considerable extent beyond the face 12 of the head. In said position the block is normally held by a strong coil-spring 18 placed inside of the hollow head. 19 is a handle for taking hold of in moving and placing the device in position. It also serves to brace the head 11.

In the use or operation of the device the operator, knowing the place where the car is to be stopped, places the device on one of the rails in the position shown in the drawing, 70 and as one of the wheels of the car rolls upon the flange 8 it presses said flange firmly against the face of the rail and thereby prevents sliding of the device. The wheel then strikes the block 14 and compresses the 75 spring 18 more or less according to the impact; in most instances the wheel may reach the face 12 of the head, but whether it does or not, the spring is supposed to re-act and, after serving as a cushion to deaden the 80 sound and take the blow of the wheel and stop the car, will expand again sufficiently to push the car with the wheel off from the device, so the latter may be removed to other parts of the track for likewise stopping other cars. Car tracks are hardly ever 85 so much inclined that a car will start from its own weight, but should such a case be found, the device may be left on the rail in such a position as to prevent accidental 90 motion of the car, or the same operator may set the brake on such a car and then remove the device.

One man with a few of these devices may thus do the work of several brakemen. 95

What I claim is:

1. In a device of the class described, an angle bar having both flanges beveled at one end and at the other end a head with a segmental face arranged to meet the face of a 100

approaching car wheel, said head being hollow and having in its segmental face an aperture, a segmental-faced block pivoted with its lower end in said aperture, a spring 5 in the hollow head tending to swing the block outward in the aperture, and means for stopping the outward swinging movement of the upper end of the block when its face is some distance beyond the face of the

hollow head so as to meet the face of the 10 wheel before it reaches the face of the head.

2. The structure specified in claim 1, the springs of said spring-pressed member being strong enough to start the car sufficiently backward to set the device free after it has 15 stopped the car.

In testimony whereof I affix my signature.
ELLIS HUGO WALLANDER.
